UNITED STATES PATENT OFFICE

2,306,827

APPARATUS FOR MAKING METALLIC PIPES
AND TUBES

William T. Mohan, Pittsburgh, Pa.

Application October 24, 1940, Serial No. 362,690

2 Claims. (Cl. 80—11)

This invention relates to the manufacture of metallic pipes and tubes and more particularly to the "seamless" process employed therein.

In the manufacture of seamless pipes and tubes, molten steel is cast into large ingots which are subsequently reduced to billet size, reheated and pierced to form a tubular blank by passing the billet between a pair of rolls and over an intermediately disposed piercing point. The rolls advance the billet helically and the piercing point is carried in such manner as to resist thrust on the forward end of a mandrel bar which is free to rotate with the billet. The tubular blank, as it emerges from the rolls, passes over the mandrel bar which, of course, must be longer than the blank to be formed. Consequently, the mandrel bar is of appreciable length as compared with its diameter, therefore tends to sag, and when rotating, whips or vibrates excessively.

It is among the objects of the present invention to restrain the excessive vibration of mandrel bars which support mandrels or piercing points in the manufacture of seamless pipes or tubes.

Another object is the provision of a device of the class described which is not only comparatively cheap and simple to manufacture and operate but one which is at the same time susceptible of use on mandrel bars which vary in length and diameter over wide ranges. There are at present devices which are constructed and arranged to restrain excessive vibration of these mandrel bars but they require changing for every change made in the diameter of the mandrel bar; and this, of course, consumes considerable time with attendant loss of production.

Other objects and advantages will appear as the nature of the improvements is better understood, the invention consisting substantially in the novel arrangement and correlation of parts herein fully described and illustrated in the accompanying drawings, wherein similar reference characters are used to describe corresponding parts throughout the several views, and then finally pointed out and specifically defined and indicated in the appended claims.

In said drawings:

Figure 1 is a diagrammatic plan of a seamless pipe or tube mill employing the apparatus of the present invention;

Figure 2 is an enlarged fragmentary plan more closely illustrating a part of the apparatus of the present invention and its correlation with the outlet bed or the mill of Figure 1;

Figure 3 is a sectional view on the line III—III of Figure 2; and

Figure 4 is a view similar to Figure 3 but disclosing the operative elements thereof in different positions to accord with other phases of the operation thereof.

Referring more particularly to the drawings, the numeral 2 generally designates a pair of power-actuated metal working rolls which are conventionally used in the manufacture of seamless pipes and tubes, the rolls in the present instance being barrel-shaped and, therefore, known in the art as being of the "Mannesman" type. Disposed between the metal working rolls 2 is a conventional mandrel 3 in the form of a piercing point which is adapted to resist the thrust of a solid billet which is gripped by the metal working rolls 2 and moved helically therethrough and, accordingly, over the piercing point 3 in order to

form a tubular blank from which a pipe or tube of the desired size is obtained. In accordance with conventional practice, the piercing point 3 is maintained against thrust by way of being carried on the forward end of a mandrel bar 4 which extends over the outlet bed of the mill, generally designated hereinafter at 5, and is carried on its rearward end by a carriage 6 which, in the operative position of the piercing point 3, is locked in order to resist thrust.

As the billet is pierced by passage between the metal working rolls 2 and over the piercing point 3 and progresses on to the outlet end of the mill, it moves over the mandrel bar 4 which, after the completion of the piercing operation, is withdrawn by the rearward movement of the carriage 6 in such manner as to free the interior of the tubular article therefrom. As the mandrel bar 4 is withdrawn over the outlet bed 5 of the mill, the piercing point 3 is freed therefrom and is replaced at a point adjacent the rolls when the mandrel bar 4 is returned to its original position preparatory to piercing another billet.

As indicated by the length of the tubular blank hereinabove designated at X, and the length of the mandrel bar 4, over which it progresses, it will be perceived that the latter, due to sagging, is subject to excessive vibration or whipping, the elimination of which is the prime object of the present invention.

Referring more particularly to Figures 3 and 4, there is extended at suitable intervals along the outlet bed 5 of the mill a pair of parallel supports 8 which lie below and extend parallel with the line of pass of the mill, which is formed by the

center line of the mandrel or piercing point 3 which is supported on the mandrel bar 4.

According to the teachings of the present invention, there is provided on the outlet bed of the mill and carried by the supports, series of rollers 10, 11 and 12. The rollers 11 and 12 are carried by parallel shafts 13 and 14 which are mounted on a suitable carriage generally designated at 16. This carriage 16 is moved in such a manner as to cause the rollers 11 and 12 to advance toward or recede from the center line of the pass of the mill in a manner which will be more fully described hereinafter.

The carriage 16 is slidably mounted on a housing 18 and is connected to a block 20 which is 15 slidably disposed in the latter. This block 20 is adjusted toward and away from the center line of the pass of the mill by means of an adjusting screw 22, which is locked in adjusted position by means of a lock nut 23. By this means the rollers 11 and 12 may be so disposed as to accommodate mandrel bars of various diameters.

The roller 10 is carried on a shaft 26 which is mounted in a bearing 27, the latter being slidably disposed in a housing 28. The bearing 27 is connected to a block 30 which is slidably disposed in the housing 28 and adjusted toward and away from the center line of the pass by means of an adjusting screw 32 which is locked in position by means of a lock nut 33.

Referring more particularly to Figure 3, it will be observed that the housings 18 and 28 have integrally formed therewith downwardly depending lever arms 35 and 36 respectively. These lever arms 35 and 36 provide central hub portions 37 and 38, respectively, through which there extends a shaft 39. Disposed below the shaft 39 is a block 42 which is mounted for reciprocation in a vertical guide 43. The block 42 carries a horizontal pin 45 to which there is pivotally connected one end of a link 46, the other end thereof being pivotally connected to the lower end of the lever arm 35. To the pin 45 there is also pivotally connected one end of a link 47, the other end thereof being pivotally connected to the lower end of the lever arm 36.

To the vertically reciprocable block 42 there is also connected the upper end of a piston rod 50, the piston of which is disposed in an air cylinder 51.

According to the foregoing construction and arrangement of parts, it will be understood that the operation of the air cylinder 51 will move the toggle links 46 and 47, and accordingly the lever arms 35 and 36, respectively, in such manner as to permit the respective housings 18 and 28 to move in scissors-like fashion to dispose the rollers 11-12 and 10 to advance toward, or recede from, the mandrel bar.

Admitting air to the bottom of the piston (not shown) on the lower end of the piston rod 50, brings the rollers 11-12 and 10 to the bar-supporting position. As the tubular blank approaches the apparatus on the outlet bed of the mill, the operation admits air to the top of the piston 51 and the rollers 11-12 and 10 recede from the bar to admit passage of the tubular blank through that portion of the outlet bed of the mill.

Other and corresponding apparatus disposed at subsequent positions in the travel of the tubular blank over the outlet bed of the mill function in the same manner.

Referring to the diagrammatic showing of Figure 1 of the drawings, the tubular blank X is 75

shown as having commenced its movement between the first series of rollers 11-12 and 10, which are in receded position; but the next series of rollers 11-12 and 10 are shown as supporting the mandrel bar 4. As stated hereinbefore, as soon as the forward end of the tubular blank approaches this series of rollers 11-12 and 10, they will be receded in the manner previously described in connection with the first series thereof.

When the piston (not shown) occupying each of the air cylinders 51 has completed its forward stroke, it is stopped by a pad 55 carried on the upper end of the vertically reciprocable block 42 in the vertical guide 43. This pad 55 makes contact with the hubs 37 and 38, and the links 46 and 47 assume the position shown in Figure 4 (i. e., that of a toggle). This position of the various elements provides for great rigidity and maintenance of the rollers 10, 11 and 12 in proper positions against the heavy stresses encountered. Due to the vertically reciprocable block 42 in the vertical guide 43, the travel of the piston rod 50 is stabilized.

As a result of the confinement of the vibration of the mandrel bar 4, there is less tendency toward variation in the wall thickness of the pipe or tube; and the life of the thrust bearing of the carriage 6 which supports the mandrel bar is lengthened.

While I have shown and described one specific embodiment of my invention, it will be understood that this embodiment is merely for the purpose of illustration and description and that various other forms may be devised within the scope of my invention, as defined in the appended claims.

I claim:

1. A mill for rolling metallic pipes and tubes, comprising metal working rolls, an intermediately disposed mandrel, a mandrel bar for supporting the mandrel in the aforesaid position, a shaft disposed beneath and in parallelism with said mandrel bar, a pair of pivoted arms extending from opposite sides of said shaft, a support carried by each of said arms, a pair of spaced rollers carried by one of said supports, the axes of said pair of rollers being substantially parallel to each other and to the axis of said mandrel bar, at least one roller carried by the other of said pivoted arms, the axis of said last-named roller being likewise substantially parallel to the axis of said mandrel bar, means for raising said pivoted arms to cause said rollers to contact said mandrel bar, and means for adjusting one of said supports with respect to the arm by which it is carried.
2. A mill for rolling metallic pipes and tubes, comprising metal working rolls, an intermediately disposed mandrel, a mandrel bar for supporting the mandrel in the aforesaid position, a shaft disposed beneath and in parallelism with said mandrel bar, a pair of pivoted arms extending from opposite sides of said shaft, a support carried by each of said arms, a pair of spaced rollers carried by one of said supports, means for adjusting said last-named support with respect to the arm by which it is carried, the axes of said pair of rollers being substantially parallel to each other and to the axis of said mandrel bar, at least one roller carried by the other of said pivoted arms, the axis of said last-named roller being likewise substantially parallel to the axis of said mandrel bar, and means for raising said pivoted arms to cause said rollers to contact said mandrel bar.

WILLIAM T. MOHAN.
